(57) **CLAIM**

The ornamental design for a ground block, as shown and described.

DESCRIPTION

FIG. 1 is a front perspective view of my new design for a ground block;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof; and,

FIG. 7 is a back elevation view thereof.

The broken line portions of the figure drawings represent unclaimed matter and form no part of the claimed design.
